[57] CLAIM

The ornamental design for a dispensing cap, as shown and described.

DESCRIPTION

FIG. 1 is a perspective view of our new design; FIG. 2 is a front elevational view of our new design, the rear elevational view being the same; FIG. 3 is a right side elevational view of our new design, the left side elevational view being the same; FIG. 4 is a bottom plan view of our new design; FIG. 5 is a top plan view of our new design; and, FIG. 6 is a bottom perspective view of our new design. The broken lines showing the bottom of the dispenser and further showing certain features on the inside of the cap are for illustrative purposes only and do not form part of the claimed design.
